Primary Examiner — Ramzi S Almatrahi*(74) Attorney, Agent, or Firm* — Price Heneveld LLP; Bradley D. Johnson(57) **CLAIM**

We claim the ornamental design for an imager housing, as shown and described.

DESCRIPTION

FIG. 1 is a front perspective view of an imager housing showing our new design;

FIG. 2 is a bottom perspective view of the imager housing of FIG. 1;

FIG. 3 is a top plan view of the imager housing of FIG. 1; FIG. 4 is a bottom plan view of the imager housing of FIG. 1;

FIG. 5 is a first side elevational view of the imager housing of FIG. 1;

FIG. 6 is a second side elevational view of the imager housing of FIG. 1;

FIG. 7 is a front elevational view of the imager housing of FIG. 1; and,

FIG. 8 is a rear elevational view of the imager housing of FIG. 1.

The broken lines depict portions of the imager housing in which the design is embodied that form no part of the claimed design.
